UNITED STATES PATENT OFFICE.

ELLIOTT P. ROSS, OF FREEPORT, NEW YORK.

HOMOGENIZING AND HEATING DEVICE FOR GASEOUS FUEL.

1,160,327.

Specification of Letters Patent.

Patented Nov. 16, 1915.

Application filed May 12, 1915. Serial No. 27,652.

To all whom it may concern:

Be it known that I, ELLIOTT P. Ross, a citizen of the United States, residing at Freeport, in the county of Nassau and State 5 of New York, have invented certain new and useful Improvements in Homogenizing and Heating Devices for Gaseous Fuels, of which the following is a specification, reference being had to the accompanying drawings.

10 My present invention relates to new and useful improvements in mixing devices for internal combustion engines and as its principal object aims to provide a device of this 15 character which is formed in the nature of an attachment adapted to be inserted between the carbureter lead pipe and the intake manifold, and is so constructed that it will serve both as a homogenizer for 20 thoroughly mixing the constituents of gaseous fuel passing into the manifold, and as a heating element for volatilizing the fuel.

Another object of the invention is to provide a carbureting device which is possessed of the above characteristics, but which 25 is extremely simple in construction and may be readily applied to or removed from an engine, with a minimum expenditure of time and labor.

30 Another and more specific object of the invention is to provide a mixing device consisting essentially in, a laminated gasket having a relatively large opening disposed to register with the passage through the 35 manifold, and an electrical resistance element which consists in a single length of wire which is passed back and forth across the opening and whereby when an electrical current is passed through the wire, this 40 member may serve as a heating medium for raising the temperature of the passing gases and consequently volatilizing them, and may also act as a homogenizing element by breaking up the passing gases, thereby 45 causing a more intimate mixture of the constituents of the fuel.

Another specific object of the invention is to pass the wire back and forth across the opening in the gasket in such manner that, 50 in effect, the opening is traversed by two superposed series of wires, the wires of each series being parallel to each other, but being diagonally arranged with respect to the wires of the other series, whereby the

range of the heated zone, created by the 55 wires will be of maximum extent.

The above, and other incidental objects of a similar nature, which will be hereinafter more specifically treated are accomplished by such means as are illustrated in the accompanying drawings, described in the following specification, and then more particularly pointed out in the claim which is appended hereto and forms part of this application.

With reference to the drawings, wherein there has been illustrated the preferred embodiment of this invention, as it is reduced to practice, and throughout the several views of which similar reference numerals 70 designate corresponding parts—

Figure 1 is a detail perspective view illustrating the carbureting device as applied to the intake manifold of a gas engine; Fig. 2 is a top plan view of the device removed 75 from the manifold; Fig. 3 is a section on the line 3—3 of Fig. 1; Fig. 4 is a detail view in top plan of the central lamination of the gasket with the homogenizing and heating wire applied to the opening therein.

In its preferred embodiment, the mixing device of the present invention is designed for application to the engine by being placed between the coupling flanges A and B of the carbureter lead pipe and the intake 80 manifold. As will be apparent upon reference to Fig. 1, the gasket takes the place of the ordinary sealing gasket which is interposed between the flanges A and B so that while this member may be omitted 90 when the present device is employed, its function is retained.

Referring now to Fig. 2, it will be seen that the gasket is substantially semi-circular in shape so that when it is inserted between 95 the elliptical flanges A and B, an extending portion indicated at C in Fig. 1, will project beyond the flanges A and B, whereby the binding posts 10 and 11 will be spaced from the manifold and will be disposed in 100 such position that lead wires from the storage battery, dry battery or generator of the automobile may be readily connected to the resistance element of the device. The gasket is preferably built up by three laminations 12, 13 and 14, which members are cemented or otherwise suitably secured to each other. A relatively large circular open-

ing, indicated at 15, is of course, formed in the gasket for the passage of the gases from the carbureter pipe into the intake manifold. On each side of the opening 15 are formed 5 smaller openings or apertures 16^a through which connecting bolts 16^b of the flanges A and B may be passed.

As a means for homogenizing and volatilizing the gases passing through the opening 10 15, I employ, as best shown in Fig. 4, a single length of wire, the terminals of which are secured to the binding posts 10 and 11. This wire is preferably formed of iron, zinc 15 or some similar metal, or if desired, a metallic composition, which is possessed of a relatively high specific resistance. In weaving the wire in the desired manner, back and forth across the opening 15, I provide at diametrically opposite portions of the opening, a plurality of small apertures, indicated 20 at 16 and 17. The apertures 16 are equi-distantly spaced from each other as are the apertures 17 and the spaces between the apertures 16 are equivalent to the spaces between the apertures 17. The one end of the 25 wire is first passed through an additional opening 18 formed at the end of the series 16, which aperture is in transverse alignment with the binding post 10. The wire is 30 passed from the binding post across the upper face of the gasket, then down through the opening 15 and thence up through the opening 18. The wire is then returned back across the opening, as at 19 to extend diagonally to the portion 20 of the wire which 35 leads from the binding posts to the apertures 18. The wire is then passed down through the first opening of the series 17 and is then directed straight across the opening 15 to the first aperture of the series 16, providing a portion 21 which is parallel to the portion 20. The wire is then passed up through the first aperture of the series 16 and next directed across the opening, producing a portion 22 which extends parallel 40 to the portion 19, but diagonally with respect to the portions 20 and 21. The wire is then passed down through the second aperture of the series 17 and then directed 45 across the opening 15 in parallel relation to the strands 20 and 21 and then up through the second opening of the series 16. Thus the wire is woven back and forth 50 across the opening 15, until it is passed through the terminal aperture of the series 16. After being passed through this aperture, the wire is passed back across the opening 15 and secured to the binding post 11. It should be noted that the binding posts 55 10 and 11 are spaced from each other a distance equal to the space between the terminal apertures of the series 16, so that the terminal strands 20 and 23 extend in parallel 60 relation to each other. It will now be apparent that the wire is passed back and 65

forth through the opening 15 in such manner to provide two superposed series of wires or resisting elements and that while the wires of each series are parallel to each other, they extend diagonally with respect 70 to the wires in the other series.

This particular arrangement of the wires has been evolved after considerable experimentation and has been embodied in the present invention, since it is found that after 75 this arrangement, the homogenizing properties of the device are materially enhanced and the effective range of the heated zone, which is created when an electrical current is passed through the wire, is materially increased. In this connection, it will be apparent that this zig-zagging of the wires will, of course, have the effect of breaking up the passing volume of gas into a number of irregularly shaped currents which will, 80 after passing through the carbureting device, readily intermingle to more thoroughly and intimately mix the constituents of the gas. It will also be observed that by arranging the two series of wires in superposed relation to each other and by disposing the wires in each series in diagonal relation to the wires of the other series, the heat generated in the different portions or strands of the wire, will be radiated in a 85 number of lines, each of which effects a different portion of the zone to be heated, so that the heat is effectively and uniformly distributed over the entire zone instead of being concentrated along a number of common lines or points. 90

The wire is, of course, applied to the central lamination so that the upper and lower lamination may serve as insulating elements for insulating the wire from the metal flanges A and B. It will, of course, be understood that the gasket is adapted for relatively permanent application to the engine so that it may serve at all times, as a homogenizer. It will be apparent that the wire 105 is used as a heating element only in cold weather and when the engine is to be started, for at such times only is it necessary to produce, by an added heating medium, a rise 110 in temperature of the gases to produce rapid 115 volatilization.

In reduction to practice, it has been found that the form of this invention illustrated in the drawings, and referred to in the above description as the preferred embodiment, is 120 the most efficient and practical; yet realizing that the conditions concurrent with the adoption of this device will necessarily vary, it is desirable to emphasize the fact that various minor changes in the details of construction, proportion and arrangement of parts may be resorted to, when required, 125 without sacrificing any of the advantages of this invention, as defined by the appended claim. 130

What is claimed is:—

A homogenizing and heating device for gaseous fuels comprising a gasket composed of a laminated body of three pieces, an electric resistance wire woven across the opening in the center lamination of the gasket, the outer laminations serving to insulate the wire from the carbureter and intake manifold, and binding posts carried by the gasket,

the ends of the resistance wire being connected to said binding posts.

In testimony whereof I hereunto affix my signature in the presence of two witnesses.

ELLIOTT P. ROSS.
